ADJUSTABLE CHAIR

Marcel Henri Grassi, Clamart, France

Application November 7, 1934, Serial No. 751,900
In France November 22, 1933

9 Claims. (CL 155—38)

The present invention has for its primary object to provide an adjustable chair utilizable particularly by children, the construction of this chair being such as to permit selective adjustment of its component parts so as to suit the increasing size of a child as he grows, so that the chair can be used without structural modifications for a period of about ten years or more or in different places where the child must sit down at different levels above the ground.

A further object of the invention is to provide an adjustable chair whose component parts may be folded up or collapsed into a small volume when in inoperative position or may be alternatively held with the required stability when in operative

position. Still a further object of the invention is to provide an adjustable chair wherein the seat has locking means which preclude any undue collapse of the latter when in operative position while being instantaneously disengageable for permitting the chair to be folded up into its collapsed position of rest.

A still further object of the invention is to provide an adjustable chair wherein the seat is so hingedly connected to pivoted members jointedly connected to the chair uprights that when said uprights and members are brought together or extended the seat can follow the folding or extending motions thus imparted to them so as to assume various adjusted positions in height responsive to the relative positions occupied by said uprights and members.

Still another object of the invention is to provide a new or improved adjustable chair made up of a minimum number of light and simple parts and capable of being manufactured and assembled at a minimum cost as regards raw materials and labor.

With these and such other objects in view as will incidentally appear hereafter, the invention comprises the novel construction, combination and arrangement of parts that will now be described with reference to the accompanying diagrammatic drawing forming a part of the present disclosure and showing by way of example a suitable embodiment of the invention.

As illustrated in the drawing, each pair of cross bars or battens X pivotally connected to each other at A is pivotally connected to the spaced uprights M¹, M² at its lower ends by pins B and C. The upper ends of the cross bars X are pivotally connected to the uprights by pins F, K slidably guided in slots or mortises D, E formed in the uprights respectively.

The seat S which may be of any suitable construction (for instance of wickerwork or upholstered structure) is hingedly connected at its fore end to the pins or axes F by means of which the fore upper ends of the cross bars X are pivoted to the fore uprights M². Teeth, notches, recesses or a rack G are provided on the back portion of the seat S, advantageously on its lower face as shown. Any one of the notches or hollows of the toothed portion or rack G may be selectively brought into registration and into removable engagement with the pins K, should the latter project inwardly of the uprights to a sufficient extent, or with a cross rod bridging and connecting the back upper ends of the cross bars X. As such a connecting cross rod corresponds in position with the pins K, it is not designated by a separate reference letter in the drawing.

Thus by engaging the pins or the cross rod K into the one or the other of the notches or recesses G formed in the seat S, after having closed or opened the cross bars X after the fashion of scissors, the height of the seat S with respect to the bottom ends of the uprights M¹, M² may be adjusted very easily to suit the size of the child, whereafter the selected position of adjustment may be preserved. In other words, the seat S and cross bars X form an articulated unit pivotally connected to the uprights forming the frame of the chair and adjustable heightwise by moving said uprights towards or away from one another after having unlocked the seat S from the pins K or from the aforesaid cross rod K.

The foot rest N is a separate fitting which, in the embodiment illustrated, has parallel cranked arms O provided with pins P which may be selectively engaged into notches or recesses H formed in the fore uprights M². These notches or recesses may be perpendicular or oblique to the longitudinal geometrical axes of said uprights, and they may be constituted, if found more convenient, by the hollow spaces between the teeth of racks fixed to the uprights in any suitable way. The foot rest N may be adjusted at will to suit the length of the child's legs, due regard being paid to the height at which the seat S has been adjusted.

The arm rests Q are connected by pivots L to the tops of the fore uprights M² of the chair. Slots I formed in the arm rests Q permit a slideable motion of the pivots U which connect them to the back uprights M¹ of the chair. This arrangement permits the arm rests to be folded up along the general plane into which the chair

is collapsed when brought into inoperative position. Clamping knobs J of any known or approved construction are provided for locking the pivots U and thus for holding the arm rests Q in their operative position (as shown) or in their inoperative position. Said clamping knobs J may be roughened or knurled to facilitate the grip on them of the user.

The uprights M¹, M² are provided, in the embodiment illustrated, with downwardly extending legs or supports V¹, V² which are pivoted to said uprights by means of the pins B, C. The legs V¹, V² are fitted with rollers R¹, R². Castors or like members can also be used instead of these rollers to permit the chair to be more easily pushed here and there and driven along the ground even by the child himself eventually, when the legs V¹, V² are in their raised positions.

Means are provided for locking the legs V¹, V² in their raised positions (as shown in full lines) or in their lowered positions (as shown in dotted lines). In the present embodiment, said means consist, on the one hand, in cleats W¹, W² secured to the uprights adjacent their lower ends and, on the other hand, in notches Y¹, Y² formed in the legs V¹, V² adjacent their pivotal connections. When the legs are brought into their lower positions, their notches Y¹, Y² snap over the free edges of the cleats W¹, W² which hold the legs firmly until said cleats are disengaged from the notches Y¹, Y².

The legs V¹, V² may have any convenient shape and may diverge downwardly as illustrated for ensuring the required stability of the chair when in lowered positions.

A small table such as T may be fitted to the chair and held as represented fixedly or removably by any approved or known device, for instance by pivots or by a slot and pin connection. Such a connection is not shown as it forms no part of the invention.

The adjustable chair as above described may be made mostly of wood, metal or any other suitable material. It can be used either in residential or in commercial premises, for instance in hair-dressers' salons for permitting the hair of a child to be more easily cut since his seated body can be raised above the floor to the most suitable height for the hair dressing operation. Other fields of utilization of this adjustable chair are obvious.

The constructional details of the chair might vary of course without departing from the spirit of the invention.

What I claim is:—

1. An adjustable chair comprising two pairs of spaced uprights, two pairs of pivoted cross bars pivotally connected at their upper and lower ends to said respective uprights, means on the uprights allowing a sliding motion of the pivots connecting the uprights to the upper ends of the cross bars, a seat hingedly carried by the fore upper ends of the cross bars, abutment means on the back upper ends of the cross bars, and locking means on the seat engageable with said abutment means, the seat and cross bars forming an articulated unit pivoted to the uprights and adjustable heightwise by moving the latter towards or away from one another.

2. An adjustable chair comprising two pairs of spaced uprights, two pairs of pivoted cross bars pivotally connected at their upper and lower ends to said respective uprights, slots in the uprights for allowing motion of the pivots at the upper ends

of the cross bars along the uprights, a seat hingedly carried by the fore upper ends of the cross bars, abutment means on the back upper ends of the cross bars, and locking notches on the seat engageable selectively with said abutment means, the seat and cross bars forming an articulated unit pivoted to the uprights and adjustable heightwise by moving the latter towards or away from one another.

3. An adjustable chair comprising two pairs of spaced uprights, two pairs of pivoted cross bars pivotally connected at their upper and lower ends to said respective uprights, means on the uprights allowing motion of the pivots at the upper ends of the cross bars along the uprights, a seat hingedly carried by the fore upper ends of the cross bars, a cross rod bridging the back upper ends of the cross bars, and a row of notches on the seat engageable selectively with said cross rod, the seat and cross bars forming an articulated unit pivoted to the uprights and adjustable heightwise by moving the latter towards or away from one another.

4. An adjustable chair comprising two pairs of spaced uprights, two pairs of pivoted cross bars pivotally connected at their upper and lower ends to said respective uprights, slots in the uprights for allowing a sliding motion of the pivots at the upper ends of the cross bars along the uprights, a seat hingedly carried by the fore upper ends of the cross bars, a cross rod bridging the back upper ends of the cross bars, and a row of indentations on the lower face of the seat, said indentations being engageable selectively with said cross rod, the seat and cross bars forming an articulated unit pivoted to the uprights and adjustable heightwise by moving the latter towards or away from one another.

5. An adjustable chair comprising two pairs of spaced uprights, two pairs of pivoted cross bars hinged at their upper and lower ends to said respective uprights, means on the uprights allowing a sliding motion of the pivots at the upper ends of the cross bars along the uprights, notches in the fore uprights, a foot rest having projections engageable with said notches, a seat hingedly carried by the fore upper ends of the cross bars, abutment means on the back upper ends of the cross bars, and locking means on the seat engageable with said abutment means, the seat and cross bars forming an articulated unit pivoted to the uprights and adjustable heightwise by moving the latter towards or away from one another when the abutment means and locking means are disengaged from one another.

6. An adjustable chair comprising two pairs of spaced uprights, two pairs of pivoted cross bars hinged at their upper and lower ends to said respective uprights, means on the uprights allowing a sliding motion of the pivots at the upper ends of the cross bars along the uprights, slotted arm rests spanning the uprights and hinged thereto, one of the hinges of each arm rest being slidable through its slot, a seat hingedly carried by the fore upper ends of the cross bars, abutment means on the back upper ends of the cross bars, and locking means on the seat engageable with said abutment means, the seat and cross bars forming an articulated unit pivoted to the uprights and adjustable heightwise responsive to a motion of the uprights towards or away from one another after disengagement of the abutment means from the locking means on the seat.

7. An adjustable chair comprising two pairs of spaced uprights, two pairs of pivoted cross bars

hinged at their upper and lower ends to said respective uprights, slots in the uprights for allowing a sliding motion of the pivots at the upper ends of the cross bars along the uprights, slotted arm 5 rests spanning the uprights and pivoted thereto, one of the pivots of each arm rest being slideable through its slot, a clamping knob for said last-named pivot, a seat hingedly carried by the fore upper ends of the cross bars, a cross rod bridging 10 the back upper ends of the cross bars, and a row of indentations on the lower face of the seat, said indentations being engageable selectively with said cross rod, the seat and cross bars forming an articulated unit pivoted to the uprights and adjustable heightwise responsive to a motion of the 15 uprights towards or away from one another after disengagement of the indentations from the cross rod.

8. An adjustable chair comprising two pairs of spaced uprights, two pairs of pivoted cross bars pivotally connected at their upper and lower ends to said uprights, slots in the uprights allowing motion of the pivots at the upper ends of the cross bars along the uprights, supporting legs fitted at 20 the lower ends of the uprights, a seat hingedly carried by the fore upper ends of the cross bars, abutment means on the back upper ends of the cross bars, and locking means on the seat engageable 25

with said abutment means, the seat and cross bars forming an articulated unit pivoted to the uprights and adjustable heightwise responsive to a motion of the uprights towards or away from one another after disengagement of the abutment means from the locking means. 5

9. An adjustable chair comprising two pairs of spaced uprights, two pairs of pivoted cross bars hinged at their upper and lower ends to said uprights, slots in the uprights allowing motion of 10 the pivots located at the upper ends of the cross bars along the uprights, supporting legs fitted with rollers and pivotally connected to the lower ends of the uprights, means for holding said legs in raised and lowered positions respectively, a seat 15 hingedly carried by the fore upper ends of the cross bars, an abutment cross rod spanning the back upper ends of the cross bars, and a row of indentations on the lower face of the seat, said indentations being engageable selectively with said cross rod, the seat and cross bars forming an articulated unit pivoted to the uprights and adjustable heightwise responsive to a motion of the 20 uprights towards or away from one another after disengagement of the cross rod from the selected 25 indentation.
